UNITED STATES PATENT OFFICE.

ERIC RICHARD LUNDIUS, OF BROOKLYN, NEW YORK, ASSIGNOR TO MACDONALD-JENSEN MANUFACTURING CO., OF BROOKLYN, NEW YORK, A CORPORATION OF DELAWARE.

BOOK HOLDER.

Application filed November 5, 1920. Serial No. 421,978.

My invention relates to new and useful improvements in a book holder and has for its primary object the construction of a device of this character which normally supports the book in a vertical position but which may be raised to inclined or horizontal position so that the book may be opened.

Another object resides in the provision of means whereby the book may be automatically opened when raised into inclined or horizontal position and in which the book will be automatically closed when again lowered into vertical position.

A further object consists in providing novel means for supporting the holder in inclined or horizontal position and releasing means for enabling the holder to be returned to vertical position.

With the above and other objects in view my invention consists of the novel details of construction and arrangement of parts which will be more clearly understood from the following specification and drawings and while I have illustrated and described the preferred embodiment of the invention it will be understood that such changes may be made as will fall within the scope of the appended claims.

In the drawings:—

Figure 1 is a side elevation showing the holder in position for supporting the book in vertical position.

Figure 2 is a front elevation showing the parts for supporting the book in vertical position.

Figure 3 is a rear elevation showing the parts in position for supporting the book in inclined position, the book supporting wings being broken away.

Figure 4 is a longitudinal vertical section.

Figure 5 is an enlarged fragmental longitudinal vertical section showing the manner of holding the end of the supporting arm in engagement with the supporting ratchet teeth.

Figure 6 is a transversely vertical section on the line 6—6 of Figure 4 and

Figure 7 is a fragmental top plan.

In carrying out my invention I provide a bracket 1 shown in fragment in Figure 1 of the drawings, and this bracket may be secured to the wall, a desk, or other suitable support. I have not illustrated the detail construction of the bracket but it will be understood that it may be of such construc-

tion as to be connected to the support by ordinary wood screws or may have an adjustable clamping screw. A plate 2, of the shape more particularly shown in Figure 1 is pivotally connected to the bracket 1 by 60 means of a pin 3 which passes through openings in the arms of the bracket 1 and eyes 4 formed on the end of the plate 2. The plate 2 is of such a shape as to extend upwardly at an angle from the bracket 1 65 and has eyes 5 formed on the upper end to receive a pivot pin 6.

A supporting member 7 is pivotally connected to the upper end of the plate 2 by the pivot pin 6 which passes through ears 70 8 formed on the back of said supporting member. This supporting member has the flared lips 9 formed on the upper end for a purpose which will later appear. Horizontal extending ears 10 are formed on the 75 front of the supporting member 7 adjacent the upper end thereof, and ears 11 are formed thereon at the lower end. A washer 12 is held upon the pivot pin 6 between the upper eye 5 of the plate 2, and the upper 80 ear 8 of the supporting member 7 and this washer is provided with a downwardly extending forked flange 13 which is adapted to engage the upper edge of the plate 2 so as to be held against rotation on the pivot pin 85 6. The front end of this washer 12 is adapted to be engaged by the back of the supporting member 7 so that the horizontal swinging movement of said supporting member will be limited with respect to the 90 plate 2.

Pivots connected at 14, between the ears 10 of the supporting member 7, is the upper end of the book rest 15. This book rest 15 is channel shaped in cross section and is 95 provided at its lower end with a finger loop 16 which may be engaged for raising and lowering the book rest 15 with respect to the support 7. Received in the channel shaped book rest 15, intermediate the ends 100 thereof, is a channel shaped plate 17 having the elongated opening 18 therein. The channel shaped plate 17 is provided on the upper end with a flange 19 and on the lower end with a tongue 20 through which rivets 105 or other suitable fastening means may be passed for securing the plate to the book rest 15. Horizontal extending eyes 21 are formed on the sides of the plate 17 at the lower end, and extend beyond the sides of the book 110

rest 15. Just above the eyes 21, and at right angles thereto, the plate is formed with tongues 22 and similar tongues 23 are formed adjacent the upper end of said plate. 5 A plate 24 is secured in the channel of book rest 15, adjacent the upper end thereof, and has the eyes 25 formed on each end thereof and extending beyond the side edges of the said book rest 15. These eyes 25 are in alignment with the eyes 21 and receive the rods 26 for pivotally connecting the book supporting wings 27. As shown more particularly in Figure 2, the rods 26 are bent to form the offsets 28 so that by increasing or 10 diminishing, said offset, the space between the wings 27 may be varied to accommodate books of different thickness. The upper ends of the rods 26 are bent at an angle as shown at 29 and are adapted to engage the 15 under side of the flared lips 9 of the support 7.

Ratchet teeth 30 are pressed from the face of the book rest 15, as more clearly illustrated in Figures 2, 4, and 5 of the drawings and are directly under the elongated opening 18 in the plate 17. The upper end of an arm 31 is pivotally connected at 32, between the ears 11 of the support 7 and the lower end thereof passes through the elongated opening 18 of the plate 17 as more particularly shown in Figures 3 and 5 of the drawings. A cross pin 33 extends through the arm 31, adjacent the lower end thereof, and one end of said cross pin is 35 adapted to be engaged by the bowed leaf spring 34 as more clearly illustrated in Figure 5. This leaf spring 34 normally tends to hold the end of the arm 31 in engagement with the inner face of the channel shaped book rest 15, beneath the plate 17. A plate 35 is received between the inner face of the book rest and the plate 17 and this plate 35 is of such length as to extend beyond the lower end of said plate 17 and is provided 40 with longitudinally spaced slots 36 and 37. The slot 36 receives the flange 20, of the plate 17, and the slot 37 receives the ratchet teeth 30. The connecting portion 38 between the slots 36 and 37 has its upper end beveled as 45 shown at 39 for a purpose to be later described. The lower end of the arm 31 operates in the slot 37 with the cross pin 33 riding over the top of the plate 35. The plate 35 is connected in the channel book rest 15 by means of the longitudinally spaced 50 projections 40 which extend through openings in one of the side flanges of said member. This allows one edge of the plate to be pressed away from the inner face of the channel book rest 15 by means of a finger knob 41 which is connected to the plate 35, adjacent the lower end thereof, by the shank 42. This shank 42 extends through the book rest 15 so that the finger knob 41 will be on 55 the outer face thereof.

For connecting the book to the book rest 15 I provide the longitudinally extending rod 43 which is bent at right angles, at each end, as shown at 44. These right angle extensions 44 are threaded and extend through the book rest 15 to receive the thumb nuts 45. By means of the thumb nuts 45 the rod 43 may be adjusted with respect to the front face of the book rest 15.

From the above detail description it is thought that the construction of my invention will be clearly understood. While the device may be used with any book it is primarily intended for use with a telephone book or other directory to which reference is frequently made. The bracket 1 may be secured to a wall or desk and normally the parts will be in position shown in Figures 1 and 2 whereby the book will be held in vertical position against the wall, desk, or other suitable support. As clearly shown the plate 2 will swing upon the pivot pin 3 and there will also be a slight pivotal movement between the plate 2 and support 7, the said pivotal movement being limited by the washer 12. When it is desired to refer to the book the finger hold 16 is grasped and the book rest 15 raised on the pivot 14. As the book rest is raised the lower end of the rod 31 will be brought into engagement with the ratchet teeth 30 so as to support the book rest, said book rest being adapted to be supported in either inclined or horizontal position according to the distance raised. The spring 34 engaging the cross pin 33 will securely hold the end of the arm 31 in contact with the ratchet teeth. As the book rest 15 is raised the curved portions 29, of the rods 26, will be swung away from the flared lips 9 so that the wings 27 will automatically drop to open position as shown in Figure 3 and the book thus be opened. When the wings are in opened position the offset portions 28 thereof will engage the ear 22 and 100 23 so as to limit the opening of said wings to a horizontal position. When it is no longer desired to refer to the book the finger knob 41 is pressed which thereby forces the free end of the plate 35 away from the inner face of the book rest 15. The raising of the 105 plate 35 engages the cross pin 33 of the arm 31 and disengages the end of the arm from the ratchet teeth, allowing the book rest to be lowered to vertical position. In disengaging the end of the arm from the ratchet teeth the spring 34 will be placed under tension and as the book rest is lowered the curved ends 29, of the rods 26, will engage the flared lips 9 and be turned thereby so as to close the wings 27 and thereby the book. As previously stated the book will be secured to the book rest 15 by means of the rod 43 which is passed between the leaves of the book and this rod may be inserted in the book, between the leaves at that point 110 115 120 125 130

where reference is most frequently desired.

Should someone endeavor to open the book, while in vertical position the curved ends 29, of the rods 26, will engage the lips 9, in such a manner as to raise the book rest 15 and this will prevent the dislocating or breaking of any of the parts. In lowering the book rest to vertical position the end of the arm 31 will engage the beveled portion 10 39 of the plate 35 so as to be guided over the face of said plate.

Having fully described my invention what I claim as new and desire to secure by Letters Patent is:—

15 1. A device of the character described comprising a bracket, a plate pivotally connected to the bracket, a book support, a pin for pivotally connecting the plate and book support, and a washer carried by the pin for engaging and limiting the movement of the support, said washer having a forked flange adapted to engage the edge of the plate.

20 2. A device of the character described comprising a support, outwardly curved lips formed on the support, a book rest pivotally connected to the support for vertical movement, and wings pivotally connected to the book rest, said wings having angular extensions adapted to engage behind the curved lips to normally hold the wings in closed position and to allow them to open as the book rest is raised.

25 3. A device of the character described comprising a support, outwardly curved lips formed on the support, a book rest pivotally connected to the support for vertical movement, and wings pivotally connected to the book rest, said wings having angular extensions adapted to engage behind the curved lips to automatically close the wings as the book rest is lowered to vertical position and to allow them to open as the book rest is raised.

40 4. A device of the character described comprising a support, a book rest pivotally connected to the support for vertical swinging movement, lugs formed on the book rest, wings pivotally connected to the book rest, and means for automatically opening and closing the wings as the book rest is vertically adjusted, said wings having offset portions adapted to engage the lugs when in opened position.

45 5. A device of the character described comprising a support having outwardly curved lips formed on the upper end thereof, a book rest pivotally connected to the support for vertical swinging movement, and wings pivotally connected to the book rest, said wings having extensions curved at

their ends to engage behind the curved lips of the support whereby the wings may open as the book rest is raised and be closed as the book rest is lowered to vertical position.

65

6. A device of the character described comprising a support, a book rest pivotally connected to the support for vertical swinging movement, ratchet teeth formed on the book rest, a plate secured to the book rest and having an elongated opening therein, an arm pivotally connected to the support and adapted to extend through the opening in the plate and engage the ratchet teeth, the opening forming a guide for the arm, a second plate connected to the book rest beneath the first mentioned plate for releasing the arm from the ratchet teeth, and means for operating the second mentioned plate.

75

7. A device of the character described comprising a support, a book rest pivotally connected to the support for vertical swinging movement, ratchet teeth formed on the book rest, a plate secured to the book rest and having an elongated opening therein, an arm pivotally connected to the support and adapted to extend through the opening in the plate and engage the ratchet teeth, the opening forming a guide for the arm, a second plate connected to one longitudinal edge of the book rest beneath the first mentioned plate for swinging movement, and means for operating the second mentioned plate to release the arm from the ratchet teeth.

85

8. A device of the character described comprising a support, a book rest pivotally connected to the support for vertical swinging movement and having longitudinally spaced openings along one longitudinal edge, ratchet teeth formed on the book rest, a plate secured to the book rest and having an elongated opening therein, an arm pivotally connected to the support and adapted to extend through the opening in the plate and engage the ratchet teeth, the opening forming a guide for the arm, a second plate positioned beneath the first mentioned plate, projections on one longitudinal edge of the second mentioned plate adapted to extend into the openings along the edge of the book rest, for allowing swinging movement of the second mentioned plate relative to the book rest, and means for operating the second mentioned plate for releasing the arm from the ratchet teeth.
